CAN OPENER

Joseph Palma, Jr., Chicago, Ill., assignor to The Dazey Corporation, St. Louis, Mo., a corporation of Missouri

Application July 5, 1955, Serial No. 36,820

Term of patent 14 years

(Cl. D22—2)

FIG. 1.

FIG. 2.

FIG. 3.

FIG. 4.

Fig. 1 is a top plan view of a can opener embodying the design of my invention;

Fig. 2 is a side elevational view thereof;

Fig. 3 is an elevational view of the opposite side of the said can opener, and

Fig. 4 is a front elevational view of the said can opener.

I claim:

The ornamental design for a can opener, substantially as shown.
